UNITED STATES PATENT OFFICE.

HENRY WAAS, OF SAN FRANCISCO, CALIFORNIA.

BUNG-CUTTER.

SPECIFICATION forming part of Letters Patent No. 314,086, dated March 17, 1885.

Application filed November 7, 1884. (No model.)

To all whom it may concern:

Be it known that I, HENRY WAAS, a citizen of the United States, residing at San Francisco, in the county of San Francisco and State of California, have invented certain new and useful Improvements in Bung - Cutters, of which the following is a specification.

My invention relates to a self-centering expansive hollow auger or bung - cutting tool having a series of cutting teeth or bits arranged in a circular manner around and secured to a rotary mandrel, said tool being provided with means for regulating the diameter and the degree of taper to be given to the bung.

Figure 1 is a perspective view illustrating my improved bung-cutter. Fig. 2 is a central vertical sectional view of the same. Fig. 3 is a plan view of the disk, and Fig. 4 is a plan view of the small end of the mandrel.

Similar letters of reference are used to indicate like parts throughout the several figures.

A represents the mandrel, the upper portion or half of which is made of less diameter than the lower part, and is provided with a series of slots or mortises, B, extending in a line parallel with the axial line of the mandrel and are open at their upper end. Within these slots I place the lower ends of the cutters C, which are held therein by the set-screws D, carried by the band or collar E, which surrounds the upper portion of the mandrel.

Any desired number of cutting teeth or bits may be employed, and their outer, upper, or forward ends are braced and steadied by resting within the notches or mortises F made in the disk G. The disk G is rigidly secured upon the spindle or rod H by means of a set-screw, G', Fig. 3, and has projecting from its upper face a short pin or point, I.

The spindle H passes completely through the mandrel, and is provided with a laterally-extending guide-pin, J, which engages with the slot K, cut in the lower or thickest part of the mandrel, and by this means the spindle is made rigid with the mandrel relative to axial rotation, while at the same time the said spindle is permitted to have a certain amount of play or movement forward and back, or in and out of the mandrel, the amount of such play being limited by the length of the slot K.

Around the lower end or portion of the spindle is loosely wrapped the coiled spring L, the forward end of which rests or presses 55 against the guide-pin J, while the inner end presses against the metal of the boring-machine into which the mandrel is fitted and from which it receives its rotating motion.

The mortises or open-ended slots B may be 60 made of any desired depth, but a depth equal to about one-third of the radius of the mandrel will be found most suitable, and the diameter of the bung or plug to be cut may be regulated by the insertion of splints or wedges M, 65 which are placed within the slots between the face thereof and the cutter, as shown in Fig. 2. When bungs of the smallest size are to be made, the cutters are laid up flat against the face of the slot and the splints placed upon 70 the outside, in which position they are rigidly held by the set-screws D, hereinbefore referred to.

The mortised disk G at the forward or outer end of the spindle may be removed at pleasure 75 and another of a different size substituted for it for the purpose of regulating the spread of the cutters for cutting either a larger or a smaller bung or plug than the standard size.

The operation of my improved bung-cutter 80 will be as follows, to wit: The tool having been properly placed in the boring-machine, and the blank from which the bung is to be cut placed upon its supporting or base block, the tool is brought down and the point or pin I 85 placed at the center of the bung about to be cut. The tool is now caused to rotate, and the downward pressure upon the tool being continued the bung or plug is cut, cored, or reamed out. As the cutters advance or cut their way 90 through the wood, the disk G remains in contact with the wood, or in its original position, while the cutters are forced down through the mortises F, and as the diametrical distance between the mortises F in the disk G is greater 95 than the distance between the mortises B in the mandrel A it will be readily seen that the closer the disk approaches the mandrel the farther apart will the points of the cutters be spread, thereby enlarging the circle of their cutting operation and giving the required taper to the bung. As the cutters and mandrel advance upon the spindle H the coiled spring L is compressed; but as soon as the

bung is cut the expansive power of the spring will force the rod and disk back to its original position with reference to the mandrel and cutters and force out the core which constitutes the bung or plug from between the cutters, and the tool will be ready for a repetition of the operation.

By this construction I am enabled to provide a cutting or boring tool which will automatically perform or accomplish the cutting out of the bung and give to it the requisite amount of taper, while at the same time the tool is kept centered in its original position.

Having thus described my invention, I claim and desire to secure by Letters Patent—

In a bung-cutting tool, the combination of

the mandrel A, having mortises B B and slot K, said mandrel being reduced in diameter at its mortised end, the collar E, having set-screws D D, the cutters C C, the splints or wedges M M, the spindle H, provided with guide pin J and spring L, and the notched disk G, detachably secured to the end of the spindle, and provided with a centering-point, I, substantially as shown and described.

In testimony that I claim the foregoing I have hereunto set my hand and seal.

HENRY WAAS. [L. S.]
